Application filed May 23, 1914. Serial No. 840,632. Term of patent 14 years.

To all whom it may concern:

The figure shows a water bag in elevation, and my new design consists of the representation of a large lily with leaves around it, the lily being represented as in a pond with a landscape for a background, including a

I claim:—

The ornamental design for a hot water bag as shown and described.

In testimony whereof, I affix my signature in presence of two witnesses.

FERDINAND FRANCIS BRUCKER.
